DESIGN FOR WALL-PAPER.

Design No. 12,543, dated October 25, 1881.

UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 12,543, dated October 25, 1881.

Application filed August 25, 1881. Term of patent 3½ years.

To all whom it may concern:

Be it known that I, EDUARD LEISSNER, of New York, in the county and State of New York, have invented a new and original Design 5 for Wall-Paper and Similar Fabrics, of which the following is a specification.

This invention relates to a new and original design for wall-paper and similar fabrics; and it consists in the novel grouping and configuration of parts, hereinafter more fully described.

The accompanying photograph illustrates a face view of a wall-paper bearing my new design.

G, H, and I are the figures composing this 15 paper. The figure G is circular, its rim being a dotted circle within which is another dotted circle, and within that are other circles. The figure H is of oval outline with pointed projections, and contains within its middle rose-like ornaments. The figures I are rows of rosettes of peculiar structure, each having a star-shaped center, and around it rays that are formed obliquely on the points thereof. The interstices between these figures are partly oc-

cupied by flower-like figures resembling pansies. The larger of these alternate with the figures I, while the smaller ones cluster about the figures G in groups of four.

The background of the design consists of a series of connected hexagons resembling the 30 cells of the honey-bee.

I claim—

1. The design for wall-paper, consisting of the figure G, substantially as shown.
2. The design for wall-paper, consisting of 35 the figure H, substantially as shown.
3. The design for wall-paper, consisting of the figure I, substantially as shown.
4. The design for wall-paper, consisting of the figures G, H, and I, substantially as shown.
5. The design for wall-paper, consisting of 40 the figures G, H, and I, with interspersed flower-figures and the background composed of a series of hexagons, substantially as shown.

EDUARD LEISSNER.
